UNITED STATES PATENT OFFICE

131,033

DESIGN FOR A MONOSCOPE ELECTRODE PLATE

Hannah C. Moodey, Plainfield, N. J., assignor to
Radio Corporation of America, a corporation of
Delaware

Application October 31, 1940, Serial No. 96,235

Term of patent 14 years

To all whom it may concern:

Be it known that I, Hannah C. Moodey, a citizen of the United States, residing at Plainfield, in the county of Union, State of New Jersey, have invented a new, original, and ornamental Design for a Monoscope Electrode Plate, of which the following is a specification, reference being had to the accompanying drawing, forming a part thereof, in which:

Figure 1 is a plan view of a monoscope electrode plate embodying my new design; and Figure 2 is an edge view of the electrode shown in Figure 1.

I claim:

The ornamental design for a monoscope electrode plate, substantially as shown.

HANNAH C. MOODEY.
